UNITED STATES PATENT OFFICE.

ORLANDO HOMER BROWN, OF VICTORIA, BRITISH COLUMBIA, CANADA.

GRAIN ELEVATOR.

1,422,534.

Specification of Letters Patent.

Patented July 11, 1922.

Application filed February 24, 1921. Serial No. 447,522.

To all whom it may concern:

Be it known that I, ORLANDO H. BROWN, a citizen of the Dominion of Canada, residing at Victoria, in the county of Victoria and Province of British Columbia, have invented certain new and useful Improvements in Grain Elevators, of which the following is a specification.

The present invention relates to improvements in grain elevators and the principal object is to provide a device of the character set forth, which is adapted for connection to grain carrying vehicles, whereby the grain may be conveyed or elevated into the storage elevator or grain car.

A further object of the invention is to provide a grain conveyor, the elevating mechanism of which is automatically operable and which is so constructed as to be readily transferred from place to place.

Another object of the invention is to provide suitable knockdown supporting means for the elevator.

With these and other objects in view, the invention consists in the construction, combination and arrangement of parts as will be hereinafter fully described, illustrated in the accompanying drawings, and pointed out in the claims hereunto appended.

Figure 1 is a detail elevational view of the improved elevator, illustrating the application of the same to a vehicle and storage elevator.

Fig. 2 is a longitudinal section through the elevator.

Fig. 3 is a vertical transverse section on line 3—3 of Fig. 2, the lower flight of the conveyor being omitted.

Fig. 4 is a fragmental magnified elevation of the upper end of the elevator, with a part of the outer casing removed.

Fig. 5 is a plan elevation of the same.

Fig. 6 is a fragmental perspective view of the conveyor chain.

Fig. 7 is a plan view of a bucket unit and chain.

Fig. 8 is an elevational view of a part of the chain and bucket units.

Fig. 9 is an elevation of the elevator support.

Fig. 10 is a detail section of one of the connecting members of the support.

Fig. 11 is a section on line 10—10 of Fig. 10.

Fig. 12 is a fragmental cross sectional view of the vehicle bed, to which the elevator is attached; and

Fig. 13 is a detail view of the adjusting rod for the vehicle hopper regulating plate.

Referring to the drawings, like numerals designate like parts in the various drawings.

In the transportation of grain from the field to the storage elevator, or to the railway cars, heretofore difficulty has been experienced in transferring the grain from the vehicle to the depository elevator, owing to the time and labor involved. With the obviations of these objections in view, I have provided an apparatus adapted for continuous actuation, to convey the grain from the vehicle to the storage depository, without the recourse of shovelling.

The apparatus comprises preferably a rectangular casing 5, formed of wood or sheet metal, having an upwardly directed spout 6 connected to the lower end and a downwardly directed spout 7 connected to the upper end. Shafts 8 and 9 are mounted in suitable journals 10 in the upper and lower ends of casing 5. Sprocket wheels 11 and 12 are keyed upon shafts 8 and 9 and revolve therewith.

A series of brackets 13 are riveted to the side walls 14 of the casing 5 and connected to said brackets 13 are the guide rails 15. A chain 16 is trained around sprocket wheels 11 and 12 and comprises a continuous series of alternately disposed links 17 and 18 connected together by pins 19. Each alternate link 17 is formed centrally with a rectangular opening 20 which is adapted to engage over the teeth 21 of sprocket wheels 11 and 12. Links 18 comprise spaced side bars 22 to which are connected by rivets 23, the brackets 24.

Connected to the chain brackets 24 are the bucket units 25 and 26, the former having closed ends 27, while their open ends are adapted for the reception of the open end portions of the buckets 26. The last mentioned buckets 26 are formed at one end with oppositely disposed semi-circular flanges 28, which are apertured for the pins 29, by means of which the hollow bucket units 26 are hingedly connected to the bucket units 25. A portion 30 of the base of each bucket 26 projects within the open ends of the buckets 25, so that the two buckets 25 and 26

together form transversely extending rectangular bucket units connected, as stated, to each alternate link 17 and spanning each drive link 18.

- 5   Mounted on the end of shaft 8, which projects beyond one of the side walls 14 of casing 5, is a gear 31 and likewise journaled in the side wall 14, is a pin shaft 32. A sprocket wheel 33 is keyed to the outer end 10 of the pin shaft 32 and a chain 34 is trained over sprocket wheel 33 and gear 31. A crank 35 is connected to the outer end of shaft 32 and has an operating handle mounted thereon.
- 15   The elevator casing 5 is supported in inclined position, as illustrated clearly in Fig. 1, upon a support 36, comprising the spaced uprights 37 which are connected together by the cross-bars 38. The upper ends of uprights 37 carry the connecting plates 39 formed with centrally disposed enlargements 40. The enlargements 40 are formed with transverse openings 41, in which are mounted the latch pins 42, the latter being tensioned 25 outwardly by the coil springs 43. These pins 42 are adapted to slide within the studs 44, secured to the lower surface of casing 5 and serve to hold the casing upon the support. Wire pull members 45 are attached 30 to the inner ends of the latch pins 42 and when pulled withdraw the pins 42 from within the openings in the studs 44, to release the support 36 from casing 5.

The lower spout 6 is hingedly connected 35 to the lower end of casing 5 and has suitable connecting elements 46 secured thereto, the opposite ends being attached to the casing 5.

While the greater part of the lower spout 6 is directed at an angle to the casing proper, 40 the upper end extends substantially in vertical plane. This spout 6 is adapted for arrangement in alinement with the outlet opening in the base of vehicles engaged in the transportation of grain. In this instance, vehicle 47 is provided with a base 45 opening in which is mounted a downwardly extending tubular extension 48. The lower open end of extension is normally closed by a plate 49 to which is connected the inner end of a bar or lever 50, by means of which the plate 49 is adjusted to allow the grain contained in the vehicle to pour through and into the spout 6. The grain which pours 50 through spout 6 gravitates downwardly and occupies the space 51 at the lower end of the spout and is subject to the shoveling action of the buckets.

In operation, crank 35 is manually actuated and imparts motion through sprocket 60 wheel 33, chain 34 and sprocket 31 to the elevator chain belt.

As the elevator belt is actuated, the buckets travelling in the direction of the arrow in Fig. 2, scoop up the grain accumulated in 65 the space 51. This grain is conveyed up-

wardly in the buckets and deposited into the spout 7 and passes through the spout 52 leading into the storage elevator 53.

By the pivotal connection of the bucket units, the same are enabled to pass freely 70 around the sprocket wheels 11 and 12 and likewise a relatively large amount of grain can be carried by the said buckets.

It is possible that with several slight modifications, to adapt this elevator to convey grain from the railway box cars or the ordinary grain cars. In this instance the spout 6 would be disconnected and the end 75 of casing run through the car door opening.

From the foregoing, it is thought that the 80 construction of my invention will be clearly understood, and, therefore, a more extended explanation has been omitted.

Having thus described my invention, what I claim as new, is:

1. In an apparatus for elevating grain from wagons, the combination with a casing and rotatably mounted shafts arranged therein, of gears mounted on said shafts, a chain actuated by said gears, means for 90 guiding and supporting the upper flight of said chain, a plurality of bucket sections pivoted to each other and secured to alternate links of said chains and operable therewith, means for connecting said casing to 95 the wagon and means for actuating said chain.

2. In an apparatus for elevating grain from wagons, the combination with a casing and rotatably mounted shafts arranged 100 therein, of gears mounted on said shafts, a chain actuated by said gears, means for guiding and supporting the upper flight of said chain, a plurality of bucket sections pivoted to each other and secured to alternate links of said chains and operable therewith, means for connecting said casing to the wagon, means for actuating said chain and a support for said casing.

3. The combination with a wagon having 110 a grain outlet opening, of an elevator comprising a casing, adapted for connection to said wagon, shafts rotatably mounted in said casing, gears on said shafts, a chain trained over said gears, means for guiding 115 and supporting the upper flight of said chain, bucket sections pivoted to each other and secured to alternate links of said chain, a driving gear mounted on one of said shafts, a drive shaft mounted in said casing, 120 a gear on said shaft, a chain connecting the last mentioned gears, and a crank mounted on said drive shaft and being operable to actuate buckets for elevating grain from said wagon.

4. The combination with a wagon having a grain outlet opening, of an elevator comprising a casing, adapted for connection to said wagon, shafts rotatably mounted in said casing, gears on said shafts, a chain 130

trained over said gears, bucket sections secured to alternate links and pivotally connected to each other said chain, a driving gear mounted on one of said shafts, a drive shaft mounted in said casing, a gear on said shaft, a chain connecting the last mentioned gears, a crank mounted on said drive shaft and being operable to actuate buckets for elevating grain from said wagon, and a 10 member connected to said casing for supporting the same in operative position.

5. A grain elevator comprising a casing, rotatably mounted shafts arranged in the ends of said casing, gears mounted on said 15 shafts, a chain adapted for actuation by said gears, buckets carried by said chains and said buckets formed of interconnected sections pivoted to each other and connected to alternate links.

20 6. A grain elevator comprising a casing, rotatably mounted shafts arranged in the ends of said casing, gears mounted on said

shafts, a chain adapted for actuation by said gears, buckets carried by said chains, said buckets formed of interfitting interconnect- 25 ed sections, and means for connecting said bucket sections together and to alternate links of said chain.

7. A grain elevator comprising a casing, rotatably mounted shafts arranged in the 30 ends of said casing, gears mounted on said shaft, a chain adapted for actuation by said gears, buckets carried by said chains, said buckets formed of interfitting interconnected sections, said sections 35 pivotally connected to each alternate chain link.

In testimony whereof I affix my signature in the presence of two witnesses.

ORLANDO HOMER BROWN.
